Primary Examiner — T Chase Nelson*Assistant Examiner* — Sydney Margaret Parsley(74) *Attorney, Agent, or Firm* — Viridant IP(57) **CLAIM**

The ornamental design for a personal hygiene capsule as shown and described.

DESCRIPTION

FIG. 1 is a front view of a personal hygiene capsule showing the design;

FIG. 2 is a top perspective view thereof;

FIG. 3 is a left side view thereof;

FIG. 4 is a right side view thereof;

FIG. 5 is a rear view thereof;

FIG. 6 is a top view thereof showing sections 7-7 and 8-8 along which cross-sectional views are taken;

FIG. 7 is a cross-sectional view thereof, taken along line 7-7 in FIG. 6;

FIG. 8 is a cross-sectional view thereof, taken along line 8-8 in FIG. 6;

FIG. 9 is a bottom perspective view thereof;

FIG. 10 is a right perspective view thereof; and,

FIG. 11 is a left perspective view thereof.

The subject matter shown in broken lines forms no part of the claimed design.
